UNITED STATES PATENT OFFICE.

CHARLES E. LONGDEN, OF NEW HAVEN, CONNECTICUT, ASSIGNOR TO THE SEAMLESS RUBBER COMPANY, OF SAME PLACE.

DESIGN FOR A WATER-BAG.

SPECIFICATION forming part of Design No. 29,880, dated December 27, 1898.

Application filed May 23, 1898. Serial No. 681,515. Term of patent 14 years.

To all whom it may concern:

Be it known that I, CHARLES E. LONGDEN, of New Haven, in the county of New Haven and State of Connecticut, have invented and produced a new Design for Water-Bags; and I do hereby declare the following, when taken in connection with the accompanying drawing and the letters of reference marked thereon, to be a full, clear, and exact description of the same, and which said drawing constitutes part of this specification and represents the design in perspective.

This invention relates to a design for a water-bag; and the design consists in a bag having the shape shown, and the surface of the bag ornamented as herein described, and shown in the accompanying illustration.

As herein shown, the design consist of a water-bag having curved side edges A and a mouth B. The surface of the sides of the bag is ornamented by a series of conventionalized fleur-de-lis C, arranged in horizontal rows, and the figures of alternate rows arranged in vertical line between the figures of the adjacent rows, and the said fleur-de-lis are differentiated from the surface of the bag, which is horizontally ribbed, the said surface ornamentation extending upward onto the mouth of the bag and on the binding-strip surrounding the edges of the bag, all as shown in the accompanying illustration.

I claim—

The design for a water-bag as herein shown and described.

In testimony whereof I have signed this specification in the presence of two subscribing witnesses.

CHARLES E. LONGDEN.
